SHAVING DEVICE

William J. Kendall, Lansing, Ontario, Canada

Application June 4, 1936, Serial No. 83,436

11 Claims.

(Cl. 30—43)

The principal objects of this invention are to provide a very simple form of shaving device which will clip the hairs cleanly without danger of abrading the skin and which may be readily manipulated to move it upwardly or downwardly over the face with a natural movement of the hand, tilting it at a slight angle either up or down, the cutting of the beard being effected without the use of soaps or creams.

10 A further and important object is to provide a form of shaving device which may be entirely manual in its operation or which may be electrically operated if desired.

The principal features of the invention consist 15 in the novel construction of a hollow or tubular-shaped head formed with rounded surfaces approaching a flat transverse curve which is slotted inwardly from each side to co-operate with a reciprocating blade provided with a plurality of teeth to form shearing cutters.

20 A further important feature consists in the novel construction of a mechanism for reciprocating the cutter member whereby a rocker arm for reciprocating the blade is operated by an eccentric driven through a train of gears operated by a hand-manipulated lever.

In the accompanying drawing, Figure 1 is a perspective view of my improved form of shaving device.

30 Figure 2 is an elevational detail view of the manually-operated mechanism.

Figure 3 is an edge elevational view of the device illustrated in Figure 1.

Figure 4 is an enlarged longitudinal sectional view of the cutter mechanism.

Figure 5 is an enlarged cross sectional view through the cutter device.

Figure 6 is an enlarged plan view of the outside of the cutter member.

40 Figure 7 is an enlarged plan view of the inner reciprocating cutter device.

Figure 8 is a diagrammatic illustration showing the application of the shaving device in two positions.

45 In carrying this invention into effect, I provide a handle 1 of a long ovoid shape which is provided with a straight transverse slot 2 at one end in which the rectangular bar-shaped portion 3 of the tubular cutter device 4 is rigidly secured.

50 The tubular portion 4 of the cutter device flares outwardly from the block 3 in the form of a projecting rounded surface 5 at one side and at the opposite side flares outwardly in a similar contour but of shallower or lesser dimensions and 55 this shallower curved side 6 is joined with the

higher rounded portion 5 by a flat curved portion 7, which is in a slightly diagonal relationship to the bar 3.

The tubular wall is here shown slotted longitudinally from points adjacent the ends at opposite sides of the flat curved portion 7 where its curvature merges with the curvatures of the respective portions 5 and 6 and a plurality of narrow slots 8 are cut in the flattened top portion 10 of the tubular member extending inwardly from 10 the longitudinal slots close in to the centre and the centre portion is formed with a longitudinal rib 9 which effectively reinforces the slotted flat portion 7 and forms a guide for the cutter 10 which is formed with a centre bar 11 provided 15 with a plurality of laterally extending cutter fingers 12.

The cutter bar 10 is curved to fit the underside of the curved central portion 7 of the tubular member and the downwardly flaring bar member 13 forms a sliding fit in the lower and converged portion of the tubular member immediately above the bar 3.

The fingers 12 of the cutter bar are preferably tapered at the ends and are bevelled back to form 25 cutting edges.

A cylindrical recess 14 is formed in the underside of the centre bar 11 of the cutter centrally of its length with a semispherical bottom and in this recess is inserted the ball end 15 of a rocker 30 member 16 which is pivotally mounted on a frame 17 arranged within the handle 1, the semispherical bottom formation providing a seat against which the ball end 15 is adapted to seat. The rocker member 16 extends upwardly through 35 a slot 18 in the bar 3 and a coiled compression spring 19 surrounding the upper end of the rocker member presses upwardly against the bar 11 holding the cutter blade 10 in close sliding engagement with the underside of the slotted tubular member 4 and as shown in greater detail in Figures 4 and 5 the ball end 15 may be slidably mounted on the reduced end portion of the rocker so that the spring pressure will be applied therethrough to the cutter blade 10 by reason of the spherical engagement of the ball 15 with the semi-spherical blade recess.

The rocker member 16 is adapted to be oscillated in such a manner as to reciprocate the cutter bar 11 with a very rapid motion so that the cutter fingers 12 will perform a shearing operation with the underside of the member 4 and while numerous forms of mechanisms may be devised for effecting the oscillation of the rocker 50 55

member, I have herein shown a very simple form of device as a preferred construction.

The rocker member is provided with a fork end 28 which engages a disc 21 eccentrically mounted 5 on a spindle 22 mounted in the frame 17. On this spindle is mounted a flywheel 23 and beside the flywheel is mounted a suitable gear pinion, which is not shown and which meshes with a gear 24 mounted on a spindle 25, which in turn is driven 10 by a pinion operated by a gear wheel 26. This latter gear wheel is driven through a gear and ratchet operated by a quadrant 27. This quadrant is pivotally mounted in a lateral extension 28 of the frame 17 and has a handle 29 which extends 15 outside of the casing handle 1 in such a manner as to be grasped by the hand of the user while holding the handle 1 and by a squeezing operation the handle 29 is swung inwardly on its pivot to operate the train of gears driving the 20 flywheel and eccentric disc which operate the oscillatable rocker member 16. The handle 29 is returned to the outward position by a suitable spring 30.

It will be understood that following the inward movement of the pressure handle the train 25 of gears will operate the flywheel at a high speed and this movement will continue during the return movement of the handle, so that the blade will continue to reciprocate at a high rate of 30 speed continuously during the squeezing and return movements of the handle.

The tilted formation of the tubular cutter provides a structure which will cut effectively even when the handle is tilted in a downward direction 35 as illustrated in the upper designation of the shaving device in Figure 8, and the larger rounded portion 5 of the tubular member permits of the device being tilted at a greater angle in relation to the surface of the face in an upward movement as is illustrated by the lower diagrammatic 40 illustration in Figure 8.

The open tubular structure of the cutter permits the hairs to fall clear of the cutter immediately they are sheared off and the rounded 45 surfaces 5 and 6 form channels into which the hairs fall clear of the cutter.

The sloping shape of the cutter head with the flat curved top and the rounded edges permits of an easy movement in drawing the device over 50 the face, both in a downward and upward direction and the cutting effect is uniform. With the smooth rounded surface of the cutter head the user of the device may press the device firmly 55 against the face as it is drawn thereover so as to smooth out all surface inequalities and clip the hairs close to the skin surface, there being no danger of cutting or scraping the face in any way.

The particular form of the cutter head is highly desirable and may be utilized with or without 60 the particular form of vibrator operating mechanism as described and if desired electrical vibrating apparatus may be used.

What I claim as my invention is:—

1. A shaving device comprising a head of tubular form having a flat transverse curve extending 65 into rounded side surfaces, said head being slotted longitudinally at the junction of the respective curvatures, said tubular head having slots extending inwardly from the longitudinal slots toward the centre, a toothed cutter slidably mounted to reciprocate longitudinally in intimate shearing relation to the flattened slotted portion of said tubular head, and means for reciprocating said cutter.

75 2. A shaving device composing a head of

flattened tubular form presenting an obliquely sloping flattened side terminating in rounded formations, said head being slotted longitudinally at the junction of the flattened and respective rounded portions, said flattened portion having a 5 plurality of narrow parallel slots cut therethrough extending from the respective longitudinal slots inwardly toward the centre, a toothed cutter slidably mounted on the inner side of said tubular head and engaging the inner side of the flattened 10 slotted portion, and means for reciprocating said cutter within the head.

3. A shaving device comprising a head of flattened tubular form presenting a longitudinal guide portion and having a plurality of parallel 15 slots extending transversely inwardly from the side of the flattened portion toward the longitudinal guide portion and opening into the interior of the tubular head, a bar extending longitudinally of said tubular head forming with the slotted wall 20 of the head a cavity to receive the severed hairs through said slots, said bar having a sliding guiding engagement with the inner side of the longitudinal guide portion of said head, a plurality of cutter teeth extending laterally from said bar 25 and slidably engaging the inner side of the slotted tubular head, and means for reciprocating said bar lengthwise of said tube.

4. A shaving device comprising a head of tubular form having a flat transversely curved surface slanting obliquely and merging into rounded side surfaces, one of which is of a larger radius than the other, said flat and oblique angled portion of the head being slotted inwardly from the rounded side portions toward the centre, said 35 head also having a longitudinal guideway in the under portion of the tubular cavity, a bar slidably mounted in said guideway having laterally disposed cutter teeth at either side engaging the inner side of the slotted tubular member, a rocker 40 member pivotally supported and extending into a recess in said bar, a compression spring mounted on said rocker member and holding said bar with its toothed upper portion in close engaging contact with the slotted tubular head, and means for 45 rocking said rocker member on its pivot.

5. A shaving device comprising a substantially flat tubular head having a longitudinal rib extending inwardly and running longitudinally thereof, said head having transverse slots extending inwardly from the outer sides thereof, a cutter member having a slot in the top slidably engaging said rib and provided with laterally extending cutter fingers engaging the inner side of the slotted head, a rocker member pivotally supported below said cutter bar and extending upwardly thereinto, spring means for holding the cutter member in contact with the slotted head, and means for oscillating said rocker member.

6. A shaving device as claimed in claim 5 in 60 which the rocker member is provided with a ball-shaped end and a cylindrical recess in the underside of said bar is provided with a semi-spherical bottom for seating contact with the inward end of the ball-shaped end of the rocker.

7. A shaving device comprising a handle having a transverse slot at one end, a bar mounted in said transverse slot having a flattened tubular portion extending longitudinally thereof, said flattened portion having a plurality of parallel slots 70 extending inwardly from opposite sides, a flattened cutter blade having parallel teeth co-operating with the edges of the slots in said tubular head to form shears, guide means co-operating with said cutter blade at the top and bottom, said 75

- cutter blade having a bearing socket and said bar having an opening in register with said blade socket, a rocker member pivotally mounted in the handle extending upwardly through the opening in said bar and having a rounded head operatively extending into said cutter bar socket, and means within the handle for oscillating said rocker member.
8. A shaving device comprising a tubular head having a centre guide bar portion and transverse slots extending inwardly toward said centre bar portion, a cutter member having guiding contact with said centre guide bar portion and fingers operating in shearing engagement with the edges 10 of said slots, a rocker member operatively engaging said cutter bar, eccentric means arranged within the handle for operating said rocker member, and a manually operated train of gears for operating said eccentric member.
- 10 9. A shaving device comprising a head of flattened tubular form presenting an obliquely sloping flattened side terminating in rounded formations, said head being slotted longitudinally at the junction of the flattened and respective

rounded portions, said flattened portion having a plurality of narrow parallel slots cut therethrough extending from the respective longitudinal slots inwardly toward the centre, a toothed cutter slidably mounted on the inner side of said tubular head and engaging the inner side of the flattened slotted portion, and means for reciprocating said cutter within the head, said terminal rounded formations of the head being of different radii with the flattened slotted side sloping 10 downwardly from the end of greater radius to the one of lesser radius.

10. Means as claimed in claim 2 in which a guide rib extends inwardly from the central part of the flattened head portion transversely of the 15 slots to reinforce the same and said toothed cutter being engaged in guiding contact therewith.

11. In a mechanism of the described class, a hollow shear bar having longitudinal slots defining an intermediate working portion cylindrically curved and arcuately slotted along each side of its longitudinal center line to provide 20 shearing teeth.

WILLIAM J. KENDALL.
